HEAT INSULATING PANEL

Benjamin Labaree and Robert K. Knipe, Philadelphia, Pa., assignors to Edward G. Budd Manufacturing Company, Philadelphia, Pa., a corporation of Pennsylvania

Application August 29, 1941, Serial No. 408,776

3 Claims. (Cl. 189—34)

The invention relates to a heat insulating panel and more particularly to a panel of a boiler enclosure. Such enclosures are, for instance, used on the boilers of ships. More particularly the invention relates to panels which are exposed to the combustion gases after the latter have transmitted a great part of their heat to the water in the boiler.

An object of the invention is a heat insulating panel which is light in weight and yet strong enough to withstand considerable pressure. This object is of great importance for ships where every pound saved in dead weight means a corresponding increase in payload or, in the case of war vessels in armament, fuel, cruising radius, etc.

Another object of the invention is a panel of the indicated type which can easily and speedily be assembled, and which can be made in any desired size and configuration so as to adapt it to all occurring requirements.

An object of the invention is also a panel of the indicated type which is gas-tight and which will retain this property as well as its strength for great numbers of years. The latter objects are likewise of outstanding importance for war vessels which may be laid off for years in peace time but which should be able to be taken into use again with the least delay for reconditioning in case of a sudden emergency.

The above outlined and other objects are attained, according to the invention, by a panel consisting of corrosion resistant metal, having inner and outer walls or sheets which are spaced from each other and inter-connected along their margins by a transverse wall portion, and the main portions of the walls or sheets of which are additionally inter-connected by a plurality of strips or the like. The strips serve not only for inter-bracing the walls or sheets but also for holding insulating material such as uncalcined diatomaceous earth in place.

Further objects, advantages and features of the invention will become apparent from the embodiments illustrated in the attached drawings and described in the following:

Fig. 1 is a diagrammatic end view of an enclosed boiler;

Fig. 2 is an outside view of an inner panel of the boiler enclosure made in accordance with the invention at the location indicated by the dash-and-dot diagonals in Fig. 1;

Fig. 3 is a perspective fragmentary view of that part of the inner wall of the panel surround-

ed by the dash-and-dot line 3 and viewed in the direction of the arrow 3 in Fig. 2;

Fig. 4 is a fragmentary section on a larger scale of the panel shown in Fig. 2 and of adjoining portions of the boiler enclosure and its supporting structure substantially along line 4—4 of Fig. 2;

Fig. 5 is a fragmentary sectional view similar to Fig. 4 but on a smaller scale and of another portion of the enclosure showing panels of substantially the same construction as that shown in Fig. 2 and also panels of slightly different types.

Fig. 1 shows a boiler having upper and lower drums 6. The drums are inter-connected by tubes (not shown). The entire boiler proper is encased by panels generally designated by the numeral 7.

The boiler enclosure comprises single walled outer panels 9 which are connected to each other along their flanged margins 10 and which are supported by brackets 11. The brackets are fastened to a supporting skeleton 12, 13.

The inner panel shown in Figures 2 to 4, comprises an outer wall 14 and an inner wall 15. The outer wall 14 is outwardly flanged at 16 and the flange 16 is reinforced by a band 17 of heavier gauge. The flange 16 and the band 17 are connected to one another by electric spot welding. Z-section rails 18 have one of their arms spot welded to the outer surface of the wall 14 so as to reinforce and stiffen the latter.

The inner panel 15 is likewise outwardly flanged at 19 all around its margins. The flange 19 is continued by a flange 20 extending parallel to the main portion of the sheet 15 and being directed toward the middle of the panel.

Z-formed strips, bands or the like 21 have their inner arms 22 resting against and spot welded to the unpierced outer surface of the sheet 15. The main portion 23 of the member 21 extends outwardly and the outer arm 24 rests against the inner surface of the outer sheet 14. Screws 25, preferably of the type cutting their own thread, are driven through registering holes in the sheet 14 and the flange 20, and in sheet 14 and the arms 24 of the members 21 so as to securely fasten the panel 15 to the panel 14.

Before connecting the outer and inner sheets by means of the screws 25, the trough or open top box constituted by the panel 15 and its flange 19 is filled with insulating material such as uncalcined diatomaceous earth.

As clearly shown in Figure 2, the bracing strips 21 are spaced apart and arranged substantially in the transverse planes containing the rein-

forcing strips 18 of the outer wall sheet 14, and the reinforcing effect of the strips 18 is carried through them to the inner wall sheet 15.

The completed panels are connected to the supporting framework 12, 13 by bolts 26 which may also serve for the connection of the brackets 11 supporting the outer panel 9.

The outer panel 9, the sheet 14 with its reinforcing members 17, 18 and the members 21 consist preferably of ordinary austenitic stainless steel, the strength of which has materially been increased by cold rolling. The inner sheet 15 which is exposed to the combustion gases consists preferably of another corrosion resisting material, namely of a material which can withstand the attack of those hot gases. Such material is, for instance, stainless steel containing about 25% chromium and 12% nickel.

The inner panels designated generally by the numerals 27 in Fig. 5 are substantially of the same construction as the inner panels shown in Figures 2 to 4.

The supporting beam 13 in Fig. 5 is covered by an inner panel which comprises oppositely flanged inner and outer sheets 28, 29. The flanges 30, 31 telescope into each other and are connected by welding along the line 32 after the space between the sheets 28, 29 has been filled with an insulating material. The panel is fastened to the member 13 by a bolt 33 which enters into a nut 34 which later is secured to the sheet 28 in the interior of the panel.

The panel generally designated by the numeral 35 in Fig. 5 differs only slightly from the panel shown in Figures 2 to 4. The outer sheet 36 may be of the same construction as the panel 14 only that one marginal portion 37 extends in the same plane as the main portion of the sheet so as to be connected with the marginal flange of the panel 27 at one corner of the boiler enclosure. The inner panel 38 is flanged at 39 and this flange is continued by a separate angle section member 40 having its one arm welded to the flange 30 whereas the outer arm 41 rests against the outer panel 36 to which it may be welded or screwed as to the flange 30 in Figure 4.

All the connections between adjoining panels or between panels and the structure are made gas-tight by appropriate gaskets 42.

The invention is, of course, not restricted to the illustrated and described embodiments. Anybody skilled in the art can design modifications so as to adapt the invention to specific requirements. All such modifications falling within the spirit of the invention are intended to be covered by the appended claims.

What is claimed is:

1. A light-weight metallic panel unit for boiler enclosures comprising inner and outer thin-gauge wall sheets of substantially like extent interconnected substantially continuously in their margins by a transverse wall sheet, said sheets together forming a closed box structure, spaced generally parallel reinforcing strips extending across the outside face of said outer wall sheet

and secured thereto, and relatively narrow bracing strips arranged substantially in the transverse planes of said reinforcing strips and in spaced apart relation lengthwise of said strips, said bracing strips extending between and interconnecting said inner and outer wall sheets, the closed box formed by said wall sheets being adapted to be filled with loose insulating material such as uncalcined diatomaceous earth.

10. 2. A light-weight metallic panel unit for boiler enclosures comprising an inner one-piece thin-gauge sheet constituting the bottom and side walls of an open-top box-like structure including an attaching flange integral with and extending around the margins of said side walls, and an outer thin-gauge sheet having its body fitting against the marginal attaching flange of said inner sheet and secured thereto to form therewith a closed box structure, spaced generally parallel reinforcing strips extending across the outside face of said outer sheet and secured thereto, and relatively narrow bracing strips having main bodies extending substantially normal to and between the inner and outer sheets and secured thereto through their ends adjacent the respective sheets, said bracing strips being arranged in spaced apart relation lengthwise of the reinforcing strips and disposed substantially in the transverse planes of said strips, the space inclosed by said box structure being adapted to be filled with loose insulating material such as uncalcined diatomaceous earth.

3. A light-weight panel unit for boiler enclosures comprising a shallow box-like structure fabricated of two main subassemblies of substantially similar marginal form and extent and made of light-gauge sheet metal, the one subassembly forming the outer wall of the panel and including a substantially flat wall sheet having marginal panel-attaching flanges secured thereto and spaced reinforcing strips secured to the outer face of said flat sheet, the other subassembly being an open-top box-like structure having a substantially flat bottom wall forming the inner wall of the panel, and side walls having edge flanges arranged in a common plane generally paralleling the flat bottom wall, and spaced narrow bracing strips disposed on the bottom wall so as to be substantially transversely aligned with the reinforcing strips on the outer wall in the final assembly, said bracing strips having main bodies extending substantially normal to the bottom wall and end flanges, and being secured in subassembly through one of their end flanges to the bottom wall and with their other end flanges disposed substantially in the same plane as the side wall edge flanges, the outer subassembly being brought, in the final assembly, with its flat wall sheet into overlapping engagement with the side wall edge flanges and the last-named end flanges of the bracing strips and secured thereto in the overlap, thereby completing the panel structure.

BENJAMIN LABAREE.
